DESIGN FOR A COMBINED SURGICAL ADJUSTER AND DILATOR

Oscar R. Evans, Tulsa, Okla., assignor of one-third to Mary Haskins Hickok and one-third to Thomas F. W. Haskins, both of Tulsa, Okla.

Application February 2, 1940, Serial No. 89,959

Term of patent 14 years

To all whom it may concern:

Be it known that I, Oscar R. Evans, a citizen of the United States, residing at Tulsa, in the county of Tulsa and State of Oklahoma, have invented a new, original, and ornamental Design for a Combined Surgical Adjuster and Dilator, of which the following is a specification, reference being had to the accompanying drawing, forming part thereof.

The figure is a perspective view of a combined surgical adjuster and dilator showing my new design, both sides of the device being identical.

The dominant features of my design reside in the portions shown in full lines.

I claim:

The ornamental design for a combined surgical adjuster and dilator, as shown and described.

OSCAR R. EVANS.
